US LLP(57) **CLAIM**

The ornamental design for a bottle, as shown and described.

DESCRIPTION

FIG. 1 is a top perspective view of a bottle;
 FIG. 2 is a front view of the bottle shown in FIG. 1;
 FIG. 3 is a back view of the bottle shown in FIG. 1;
 FIG. 4 is a right side view of the bottle shown in FIG. 1;
 FIG. 5 is a left side view of the bottle of FIG. 1; and,
 FIG. 6 is a top view of the bottle of FIG. 1.
 The broken lines in FIGS. 1-6 illustrate the portions of the
 bottle that form no part of the claim.
